(57) **CLAIM**

The ornamental design for a tire inflator, as shown and described.

DESCRIPTION

FIG. 1 is a perspective view of the tire inflator, according to one embodiment of this invention;

FIG. 2 is a front view of the tire inflator shown in FIG. 1; FIG. 3 is a rear view of the tire inflator shown in FIG. 1; FIG. 4 is a side view of the tire inflator shown FIG. 1; FIG. 5 is a side view, opposite the side view shown in FIG. 4, of the tire inflator shown in FIG. 1; FIG. 6 is a top, view of the tire inflator shown in FIG. 1; and, FIG. 7 is a bottom view of tire inflator shown in FIG. 1. The broken lines are included for the purpose of illustrating portions of the tire inflator that form no part of the claimed design.
